FISHING LURE

Jack E. Davis, Crescent City, Fla., assignor to Victor Comptometer Corporation, Chicago, Ill.

Filed May 1, 1972, Ser. No. 249,482

Term of patent 14 years

Int. Cl. D22—05

U.S. Cl. D22—29

FIG. 1

FIG. 2

FIG. 3

FIG. 4

FIG. 5

FIG. 6

FIG. 1 is a rear end view of a fishing lure embodying my new design;

FIG. 2 is a side elevational view thereof;

FIG. 3 is a front end view thereof;

FIG. 4 is a bottom view thereof;

FIG. 5 is another side view thereof opposite the view of FIG. 2; and

FIG. 6 is a top view thereof.

I claim:

The ornamental design for a fishing lure, as shown.
